Patented May 26, 1914.

UNITED STATES PATENT OFFICE.

GUNNAR WALINDER, OF CHICAGO, ILLINOIS, ASSIGNOR OF TWO-FIFTHS TO BERT R. WALINDER, OF CHICAGO, ILLINOIS.

PUMP.

1,097,955.

Specification of Letters Patent.

Patented May 26, 1914.

Application filed September 23, 1912. Serial No. 721,735.

To all whom it may concern:

Be it known that I, GUNNAR WALINDER, a citizen of the United States, residing at Chicago, in the county of Cook and State 5 of Illinois, have invented certain new and useful Improvements in Pumps, of which the following is a specification.

My invention relates to pumps and especially to double-acting pumps for deep wells. 10 In the prior art such pumps have been constructed with two cylinders, or with a cylinder divided into two parts. According to my invention it is necessary to employ but one cylinder, and by so doing I have reduced the number of valves necessary and 15 have made possible a more simple construction using fewer parts.

One object of my invention is to provide a double-action pump which is simple in 20 construction and has few parts.

A further object is to provide means for easily and quickly withdrawing the working parts from the well for inspection and repair.

25 A further object is to provide a pump of this character having a single cylinder, and thus to produce a shorter and more compact construction.

A further object is to provide a pump construction in which the cylinder and outer casing may be composed of ordinary piping.

In the accompanying drawings, Figure 1 is a vertical central section of a pump embodying my invention. Fig. 2 is a view 35 showing some of the working parts, the walls of the cylinder and pump casing being cut away. Fig. 3 is a transverse sectional view taken on the line 3-3 of Fig. 1. Fig. 4 is a top plan view of the pump, the 40 piston rod being shown in section.

In the present embodiment of the invention, the outer casing of the pump is composed of a cylindrical pipe 1 which is screw-threaded at the top and bottom, a lower 45 member 2 connected therewith, and an upper member 3 similarly connected at the upper end of the pipe 1. This outer portion, which is herein called the pump casing, is stationary below the bottom of an outflow pipe 4 which extends to the top of the well. 50 The pump casing is provided near its upper portion with ports 4^a for the purpose of permitting the inflow of liquid. Within

this pump casing is a longitudinally movable cylinder 5 inclosing the piston 6, and 55 partially inclosing a valve cage 7.

The pump casing terminates below with the head 8 which is provided with a conical opening to receive plug 9 which is correspondingly tapered and which may be provided with washers 10, or other packing, to insure a liquid-tight joint. The plug 9 is vertically apertured to permit the inflow of liquid into the cylinder, and terminates at its upper extremity in the valve seat 9^a, 65 adapted to coöperate with the valve 11. This valve may be of any approved form. In the embodiment selected for illustration it is a ball, and is held in place by the valve cage 7 which is connected by a screw-thread 70 with the upper portion of the plug 9.

The piston 6 is hollow and is composed of an upper member 6^a connected at its upper extremity with the piston rod 21 and a lower member 12 connected with the said upper member by screw-threads and forming at its upper extremity a valve seat 12^a 75 adapted to coöperate with the valve 13 which may be of any approved form. In the embodiment shown, the valve 13 is a ball and 80 is held in place above the valve seat by the hollow piston member 6^a. The outer surface of the piston is provided with a liquid-tight packing which may consist of the washers or cup leathers 14, or any approved 85 form of packing for such purpose. Above this packing and at the lower extremity of the piston member 6^a is an outwardly projecting flange 6^b, which is adapted to aid in removing the cylinder of the pump from 90 the well, as hereinafter described. The lower portion of the piston member 12 and the upper portion of the cage 7 are correspondingly screw-threaded for a similar purpose, 95 as hereinafter described.

The upper end of the cylindrical pipe 1 is provided internally with a left-hand screw thread into which is screwed the annular head 15, which is vertically apertured and which is provided with a valve seat 15^a 100 adapted to coöperate with the valve 16. The valve 16 is guided and held in position by the stem 16^a and is limited in its movement by the valve cage 17; it may also be provided with a spring 18 to assist in holding it in a closed position. The lower part 105

of the annular head 15 is provided with lugs 19 and the upper part of the piston 6 is provided with corresponding lugs 20, for a purpose hereafter to be described. The 5 valve 16 and the valve cage 17 are vertically apertured to permit of the passage of the piston rod 21. That portion of the piston rod 21 which extends from the piston 6 to a point above the valve cage 17 is vertically apertured to permit the passage of 10 liquid from the interior of the hollow piston and has transverse openings 22 into the outflow pipe 4.

The cylinder 5 is provided at its upper 15 extremity with an annular member 5^a adapted to engage with the projecting flange 6^b when the cylinder is to be raised from the well; and the lower extremity of the cylinder is provided with a similar annular 20 member 5^b which is adapted to embrace the lower portion of the valve cage 7 and serves to guide the cylinder in its longitudinal movement.

In operation, when the parts are in the 25 lowermost position, that part of the pump casing and movable cylinder which is above the piston is filled with liquid through the apertures 4^a. On the up-stroke of the piston the movable cylinder 5 is raised slightly by 30 the friction of the piston until its upper surface comes in contact with the lower surface of the annular head 15, thus closing the cylinder against the outflow of liquid. The further rise of the piston then forces 35 the liquid above it past the valve 16 and into the outflow pipe 4; and, downward escape of liquid being prevented by the check valve 13, this causes an upward flow of the liquid in said pipe and a consequent 40 delivery of liquid at the surface.

During the upward stroke of the piston the liquid rises through the vertical opening in the plug 9 past the valve 11 and through the apertures in the valve cage 7 45 into the interior of the movable cylinder; so that when the parts are in the uppermost position that portion of the cylinder which is then below the piston is filled with liquid which is prevented from escaping in a downward direction by the valve 11. On the 50 down-stroke of the piston this liquid is therefore forced upwardly through the interior of the hollow piston, past the valve 13 and through the hollow portion of the piston rod 21 and is delivered through the 55 transverse openings 22 into the outflow pipe 4. This additional quantity of liquid, being prevented from downward escape by the valve 16, causes an upward flow of liquid in 60 the outflow pipe and a consequent delivery at the surface. Hence, there is a pumping action both on the upward and downward stroke of the piston. During the downward stroke of the piston the movable cylinder 5 65 descends slightly and leaves open the top,

through which the liquid enters the cylinder for a repetition of the pumping action heretofore described.

I will now explain the use of the lugs 19 and 20 and the screw-threads in the lower 70 portion of the piston and on the upper portion of the valve cage 7. During the operation of pumping, the movable parts will frequently become worn so that it is necessary to replace or repair them and to withdraw them from the well for that purpose. If it is desired to withdraw the piston, it is raised as far as possible and then turned by means of the piston rod 21 until the lugs 20 come into lateral engagement with the 80 lugs 19, as shown in Fig. 3. By a further turning movement of the piston rod the valve seat 15 may then be unscrewed from its left-hand thread engagement with the pump casing, when the piston and the annular member 15 and the parts supported thereby may all be drawn to the top of the well through the outflow pipe 4. The projecting flange 6^b, coming into engagement with the annular member 5^a, carries up with the piston the cylinder also.

If it is desired to withdraw also the plug 9 and the parts which it supports, the piston is lowered until it comes in contact with the top of the valve cage 7, when by a turning movement of the piston rod, as before, the interior screw-thread on the lower part of the piston engages with the exterior screw thread on the valve cage 7, thus permitting the plug 9 and all the parts which it supports to be raised from the head 8.

When it is desired to reseat the parts in the pump casing, they may be lowered from the top of the well and fixed in their respective positions by reversing the operation 105 above described.

I do not desire to limit myself to the precise form herein shown, since the proportions, form and manner of construction may be varied without departing from the spirit 110 and substance of my invention.

I claim as my invention:

1. A double-acting pump consisting of an outer pump casing, a longitudinally movable cylinder therein, means for permitting the 115 inflow of liquid to said cylinder, a reciprocating hollow piston in said cylinder, a hollow piston rod connected with said piston and arranged to permit the flow of liquid through said rod on the downward stroke of 120 said piston, means for preventing the downward flow of liquid during said stroke, and a valve in said casing adapted to permit the upward flow of liquid during the upward stroke of the piston.

2. In a pump, in combination, a pump casing; an annular head connected with said casing by a screw-thread; lugs on said head; a piston rod; and a piston connected therewith having lugs adapted to engage the lugs 125 130

on said head for the purpose of unscrewing said head from the said pump casing.

3. In a double-acting pump, in combination, a pump casing having inlet ports near its upper and lower ends and an outflow valve at its upper end; means for closing said lower inlet port against the outflow of liquid; a reciprocating cylinder within said casing adapted to close said upper inlet port; and a hollow piston with a hollow piston rod adapted to raise liquid through said outflow valve on the upward stroke, and to force liquid upward through said piston and said piston rod on the down stroke.

15 4. In a double-acting pump, in combination, a longitudinally movable cylinder; a reciprocating hollow piston within said cylinder; a pump casing exterior of said cylinder containing liquid inlet ports; a tubular actuating rod immovably attached to the said hollow piston having a liquid delivering opening above the said pump casing; a valve within said hollow piston to prevent the downward flow of liquid through said actuating rod and cylinder, said pump casing having a port in its upper end for the exit of water from the upper end of said movable cylinder; and a valve to prevent downward flow through the last mentioned port.

20 5. In a double-acting pump, in combination, a pump casing; a longitudinally movable open-topped cylinder adapted to be closed on its upward movement by contact with the head of the pump casing; a hollow piston working in said cylinder and arranged to reciprocate said cylinder; a hollow piston rod connected with said piston and adapted to convey liquid received through said piston to a point outside the pump casing; a check 25 valve opening into said cylinder below said piston; an inlet port in said casing above said piston; a check valve in said hollow piston; and an outwardly-opening valve in the head of said cylinder above said piston.

30 6. A pump casing comprising a cylindrical pipe; a cylindrical bottom section connected therewith by screw-threads; a head connected with said bottom section by screw-

35 threads and apertured to receive a valve-supporting plug; a cylindrical top section connected with said cylindrical pipe by screw-threads; and a valve-supporting head connected by screw-threads with said pipe.

7. In a pump, in combination, a pump casing comprising a cylindrical pipe, and a cylindrical bottom section and a cylindrical top section connected with said pipe by screw-threads; a vertically apertured head screwed into said bottom section; a vertically apertured plug seated in said head; a valve supported by said plug; a vertically apertured head connected by screw-threads to the upper end of said pipe; a valve on said last mentioned head; a longitudinally movable cylinder within said casing; and a piston working in said cylinder and adapted to reciprocate said cylinder.

8. In a double-acting pump, in combination, a pump casing; a longitudinally movable cylinder therein; a reciprocating piston in said cylinder; means for delivering liquid into said cylinder alternately above and below said piston; and a check valve at the lower end of said casing adapted to prevent the escape of said liquid downwardly from said cylinder during the stroke of the piston.

35 9. In a double-acting pump, in combination, a longitudinally movable cylinder; a reciprocating hollow piston within said cylinder; a pump casing exterior of said cylinder containing liquid inlet ports; a tubular actuating rod attached to the said hollow piston having a liquid delivering opening above said pump casing and adapted to deliver liquid on the downward stroke of said piston; a valve in the pump casing above the piston adapted to permit the discharge of liquid on the upward stroke of said piston; and a ball-valve within said piston to prevent the downward flow of liquid.

40 In testimony whereof I affix my signature in the presence of two witnesses.
